HAT BLOCKING MACHINE CONSTRUCTION

Burling D. Wells, Danbury, Conn., assignor, by
mesne assignments, to John B. Stetson Com-
pany, Philadelphia, Pa., a corporation of Penn-
sylvania

Application July 3, 1943, Serial No. 493,321

16 Claims. (Cl. 223—15)

1

This invention relates to hat blocking machines.

One of the objects of this invention is to provide an improved apparatus for blocking hat bodies of the fur felt type. Another object is to provide, in a hat blocking machine, improved actuation and improved control of the various co-acting parts of the machine. Another object is to provide simple, compact and efficient mechanism for actuating in their desired sequence the various parts and mechanisms of the apparatus for loading it with a hat body to be operated upon and for actuating and controlling the various mechanisms and parts to perform the desired mechanical and other processing operations upon the hat body. Another object is to provide a hat blocking machine having simplicity and dependability of manual control in conjunction with automatic control of other parts and operations. Another object is to provide a blocking machine of the above-mentioned character that will be easier and simpler for the operator to control, more dependable and efficient in operation, and of improved performance, as compared to blocking machines heretofore known or used.

Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of my invention,

Figure 1 is a plan view of the apparatus, certain parts being broken away and certain other parts being shown in horizontal section;

Figure 2 is a vertical sectional view as seen substantially along the line 2—2 of Figure 1, certain parts being omitted or broken away to show certain other parts more clearly;

Figure 3 is a side elevation as seen from the right in Figure 2;

Figure 4 is a vertical sectional view as seen substantially along the line 4—4 of Figure 1;

Figure 5 is a detached vertical sectional view along the line 5—5 of Figure 1;

Figure 6 is a detached fragmentary vertical sectional view showing certain details of certain gripping devices;

Figure 7 is an elevation along the line 7—7 of Figure 6; and

Figure 8 is a view, principally diagrammatic,

2

showing certain electrical circuits and controls.

Similar reference characters refer to similar parts throughout the several views of the drawings.

The apparatus comprises a suitable base or frame generally indicated by the reference character 10 and preferably and conveniently in the general form or configuration of a box-like casting or housing constructed or built up in any suitable way to accommodate, or to facilitate the mounting of, the various parts of the apparatus. In the top or horizontal portion 11 of the frame 10 and secured thereto as by screws 12 (see Figure 3) so as to be supported in rigid depending relation, is a frame 13 round in horizontal cross-section and shaped as is better shown in Figure 2 to provide a relatively heavy vertically elongated sleeve-like bearing 14 for slidably supporting and guiding, for up and down movement, an elongated sleeve member or tube 15 of relatively heavy and strong construction. A suitable key and keyway, indicated at 16, provided for the parts 14 and 15 hold the part 15 against rotation during its up and down movement in the bearing 14. At the upper end of tube 15 is secured a block support generally indicated by the reference character 17 and better shown in Figure 4. Block support 17 is made preferably of a material like stainless steel and its bottom hub-like portion 18 is provided with a bore 20 to form an extension of the tube 15 and to facilitate mounting thereof onto the upper end of tube 15.

Thus the bore 20 may be counter-bored as at 19 to accommodate the upper end of tube 15 and these parts may be so dimensioned to form a press fit to achieve a secure and strong assembly and dependable alignment of the two parts.

The upper portion of the block support 17 has an oval peripheral wall 22 upstanding from an oval bottom wall 23 that extends about the bore 19, the major axis of the oval extending from front to rear as viewed in Figures 2 and 4. The oval-shaped space encompassed by walls 22 and 23 is closed over at its upper end by a perforated wall 24 that is also oval in shape, and supported over the wall 24 is a hollow metal hat crown block 26 having an oval side wall 26^a and an oval top wall 26^b, both perforated. The plane of perforated wall 24 and hence of the edge of wall 22 need not be flat but may be curved corresponding to the scope desired to give the hat body. Block 26 is preferably detachably mounted so that its major axis is aligned with the coincident major axes of the oval parts 22 and 24. For this purpose the block 26 may have at its

lower end an inturned flange 26^c provided with two apertures on its major axis to take over or onto two dowel or locating pins 27 projecting upwardly from the plane of the perforated wall 24. Preferably, to give the mounting of the crown block 26 a strong support, there extends about the perforated wall 24 a ring-like but oval member 28 dimensioned to underlie the inturned bottom flange 26^c of the block 26; the part or member 28 is secured to the outer oval wall 22 by arms 30, the parts being preferably welded to form a strong integral or unitary structure. The bottom of block 26 and the parts which it engages may also be scoped to the scope of wall 24.

The hub 18 is formed to provide an annular chamber or passage 31 which at any suitable lateral point has connected thereto a flexible pipe or conduit 32 (see also Figure 6) which, as is later described, connects with a suitable source of steam supply. The upper wall of the annular passage 31 in hub 18 is apertured as at 33, thus to emit steam into the space underneath the perforated wall 24 and the perforated hat block 26.

The block support 17, as at the upper face of the wall 23 about the bore 19, is shaped to form a seat for a valve 35 to close off the passage at the upper end of the tube 15 and extending downwardly through the latter is a valve stem 36 the lower end of which is slidably guided in a bearing formed in a relatively heavy closure cap 37 which is fitted over and secured to the lower end of the tube 15. The lower end of valve stem 36 projects below the end cap 37, where it is engaged by one end of a lever 38 fulcrumed on a pin 39 supported in suitable spaced lugs 40 integrally formed on one side of the closure cap 37. The other end of lever 38 is provided with a roller 42 for coaction with a cam 43 mounted and actuated as is later described.

Valve 35 is to remain closed during the emission of steam to the space underneath the perforated hat block 26 and related parts and is to be opened at an appropriate time in the operation of the apparatus to connect the just-mentioned space to an exhausting apparatus or any other source of suction (not shown) which is connected by a pipe or conduit 45 to a port 46 formed in the wall of the bearing 14 in which the tube 15 is vertically slidable. Tube 15 is in turn provided with a port 47, the two ports being so dimensioned and relatively positioned that, when the tube 15 is in its uppermost position as shown in Figure 4, ports 46 and 47 register and when tube 15 is in its lowered position, tube port 47 is displaced downwardly from the bearing port 46, the latter being closed off by the walls of tube 15 above port 47. When the ports register, opening of valve 35 thus connects the hollow space within the block support 17 and the hat block 26 to the suction or low pressure (that is, below atmospheric) apparatus.

Suitable means, preferably manually controlled, are provided to hold the tube 15 with its block support 17 in upward position. Such means may comprise a latch 49 loosely pivoted on a stud 50 supported in spaced lugs 51 projecting laterally from the bearing member 14 and provided with suitable connections to an operating handle 52. The latch 49 is biased in any suitable way, as by the weight of the parts, toward the axis of tube 15 and is suitably shaped so that upon upward movement of tube 15 into the position shown in Figure 4 it catches in under the end cap 37 and holds the tube 15 and related

parts against downward movement. Such upward movement of the tube 15 carries valve lift lever 38 upwardly with it and brings the roller 42 into position to be acted upon by the cam 43 which, when it depresses the lever 38 at an appropriate point in its rotary movement, thus effects lifting of the valve 35.

Release of the latch 49, by operation of the hand lever 52, permits the tube 15 and hat block support 17 to descend, closing off the suction port 46 and moving valve lift lever 38 out of the range of actuation of the cam 43.

When the tube 15 and block support are in lowermost position, a hat body indicated at H in Figure 2 and previously operated upon to have a shape approximating a crown and brim is to be related to the apparatus and this is effected by a series of gripping devices which engage and grip the brim, indicated at B, at its outer peripheral portion, the gripping devices being numerous and closely spaced so that, when in action, the outer peripheral portion of the brim is substantially uniformly gripped and held. These devices, indicated generally by the reference character 55, are all of the same construction, two of them appear in vertical cross-section as seen in Figures 2 and 4, and a detailed description of one of them will suffice for all.

Each device 55 comprises what will be termed a finger 56 projecting inwardly from and at the upper end of the vertical arm 57 of a bell crank lever pivoted at 58 in an individual bearing block 59 secured to a horizontal portion of the part 13 of the frame 10 as by screws 60; the lever having its other arm 61 projecting inwardly toward the vertically slidable tube 15. The end of arm 61 of bell crank lever 57-61 projects into an annular slot 62 of a collar 63 that is guided for up and down sliding movement by the tube 15, these two parts interfitting with a suitable sliding fit.

With all of the bell crank levers 57-61 thus mounted upon the part 13, being arranged in a circle whose center is coincident with the vertical axis of the tube 15 and hence of the perforated hat block 26, the upper faces of the fingers 56 form a substantially continuous annular or circular support (see Figure 1) upon which the outer portion of the brim B (the brim B and the crown, indicated at C, of the hat H being at this stage circular instead of oval) is rested when the hat body H is inserted into the apparatus, and thence that portion of the brim B is clamped against the fingers 56 by companion fingers 64 one for each device 55 and each hingedly or pivotally mounted at the upper end of the lever arm 57. The plane in which the faces of fingers 56 fall or are aligned is preferably scoped, and this is preferably done by giving the pivots 58 correspondingly different heights, as by giving bearing blocks 59 different vertical thicknesses above the flat face of frame part 11 so that, with all of the bell crank levers 57-61 of similar or identical configuration and dimensions and with their points of pivoting at different elevations as is clearly shown in Figures 2 and 4, their finger-end-faces 56 are at corresponding different elevations and thus define the desired scope.

For pivotal mounting of fingers 64, the upper outer end of each lever arm 57 may be shaped and machined to provide two spaced ears between which a reduced portion of the finger 64 is received and through all of which extends a pivot pin 65, forming a hinge-like joint.

The devices 55 are preferably closely spaced in their circular arrangement, and the parts 57

thereof are shaped, as by being given a U-shaped or channel section (see Figure 2, where two are shown in section) as to accommodate therein a link 67 which is pivotally connected at its upper end to the upper finger 64 as by a pin or stud 68 and which at its lower end is connected to the inner end of a relatively stiff leaf spring 70 that extends along a radius and whose outer end is anchored, as by a screw 71, to the underface of a large and strong ring 72.

The above-described U-shaped or channel horizontal cross-section of the arms 57 will thus be seen to permit closer grouping together of the devices 55 because of the accommodation within the flanges of the U-shaped section of the links 67. However, to bring the steam conduit connection 32 (Figure 1) through the circular-like array of upstanding devices 55, I prefer to make the parts of two adjacent devices 55, between which two the conduit 32 is to pass, of relatively solid construction as indicated by the reference characters 57^a in Figures 1, 6 and 7, thus to give them sufficient strength to permit cutting them away at their adjacent sides as at 57^b and 57^c in Figure 7, the cut-away portions or slots 57^b and 57^c being of substantial vertical extent in relation to the vertical dimension of the conduit 32 which can be flattened out somewhat or made oval (see Figure 7) in that portion thereof that extends through the upstanding devices 55. Thereby the two specially shaped parts 57^a—57^a can freely pivot about their lower pivots just like the other devices 55, without the conduit 32 interfering therewith or with any part of the hat body.

The links by which the upper fingers 64 of these two devices are actuated are preferably, therefore, also specially shaped, being given a curvature as shown at 67^a in Figure 6 and being pivotally connected at their upper ends to the fingers 64 and being secured to leaf springs 70 at their lower ends, just as are the links 67 of the other devices 55.

Ring 72 that carries the springs 70 is mounted for up and down sliding movement and for this purpose a convenient arrangement comprises two upstanding parallel guide bars 73 and 74, diametrically opposed with respect to the axis of the tube 15 and suitably anchored at their lower ends in the base frame 10, one adjacent each side of the latter as appears from Figure 2. The ring 72 is provided with lateral extensions forming sleeve-like or elongated bearings 75 and 76 to guide the ring 72 in its up and down movements and to maintain its plane and hence the plane of the spring anchorages 71 always at right angles to the vertical axis of the tube 15 and related parts carried by or grouped around it.

For each device 55, ring 72 thus carries an inwardly extending cantilever leaf spring to actuate a corresponding upper finger 64. Ring 72 serves also as the anchorage for one end of a biasing spring 77, one for each finger-carrying device 55. Thus one end of spring 77 is anchored to the ring 72 as by a pin extension of screw 71 and the other end is secured to the link 67, through which the spring urges the device outwardly away from the hat-block.

Springs 77 bias the finger-carrying arms 57 in a direction away from the vertical axis of the hat block, being preferably relatively light or gentle in their action, but sufficiently strong to effect the desired biasing, to an extent as determined by the upper face 62^a of the annular slot 62 in the slidable collar 63, for it is that

upper face 62^a that the ends 61 of the bell crank levers 57—61 engage to limit the outward swing or bias of the arms 57.

This upper face 62^a of the slot 62 is a plane face in that it lies in a plane that is at right angles to the vertical axis of the collar 63 and with the devices 55 grouped in a circle as above described, the coaction between biasing springs 77 and the upper face 62^a insures that the fingers 56 likewise lie in a circle and thus form a circular annular support to receive the outer portion of the circular brim B. Thus, and ultimately, each gripping device, when the companion gripping fingers 64 are brought into action, grips substantially the same radial extent of the brim B.

The companion or juxtaposed face 62^b of the annular slot 62 is, however, curved and hence is not plane and is therefore not parallel to the face 62^a. This feature is later described in greater detail and results in a variation of the width or vertical dimension of the slot 62 to permit such relative shifting of the gripping devices 55 about their pivots 58 to take place as causes the gripping fingers 56—64 to define an oval when the coaction of the lever arms 61 is shifted from the plane face 62^a to the curved face 62^b.

Having placed the hat body H onto the fingers 56, the companion fingers 64 are swung and held in upwardly tilted position during this operation of loading the machine with the hat body.

To the lateral extensions 75 and 76 (Figure 2) of the finger-controlling ring 72 are pivotally connected as at 78^a and 78^b, respectively, links 79 and 80 that extend downwardly along either side of the box-like base or frame 10 and at their lower ends links 79 and 80 are pivotally connected to the rear ends of parallel and horizontal links 81 and 82 (see Figures 3 and 4), respectively, these links being pivoted at their forward ends to the sides of the frame 10 as by suitable studs 83 and 84, respectively.

These externally mounted links 81 and 82 are slotted as at 85 and 86 to receive therein eccentrics 87 and 88, respectively, that are fixedly mounted at the respective ends of a cross shaft 90 (Figures 3 and 4) which extends crosswise of the frame 10 which, in its respective sides, is provided with suitable bearings 103 and 104 (Figure 1) for rotatably supporting the shaft 90. One extreme end of the shaft 90, that is, the end portion that extends beyond the cam 87 mounted upon its external end, has keyed or otherwise secured to it a handle 91 (see also Figure 3) by which the shaft 90 and hence the eccentrics 87—88 may be actuated to raise or lower the finger-controlling ring 72. If desired, a handle 91^a may be mounted and keyed at the other extreme end of shaft 90, for similarly actuating the latter.

Accordingly, by actuating the lever 91 in counterclockwise direction as viewed in Figure 3, eccentrics 87 and 88 are rotated sufficiently to depress the lever-like external links 81—82 and thereby, by the inter-connecting links 79 and 80, depress the finger-controlling ring 72 which thus, through the strong or relatively stiff spring action of the cantilever leaf spring 70 (Figure 2) swings the gripping fingers 64 inwardly and downwardly to clamp the outer portion of the circular brim B against the scoped annular support formed by the upper faces of the fingers 56, thus forcing the gripped portion of the brim to assume a corresponding scope. The fit of the eccentrics 87 and 88 in their respective slots 85 and 86 is such that swinging of the shaft 90 and hence of

the eccentrics in reverse direction raises the lever-like links 31—32, thus reversing the motion and action of the finger-controlling ring 72.

Having thus peripherally gripped the circular brim B, the collar 63 (Figure 2) is actuated in upward direction to swing the finger-carrying arms 57 outwardly away from the axis of the hat body, thus to tension or stretch the brim radially outwardly, but because of the scope of the gripping faces of fingers 56, the tensioning follows the scope. During this operation the tube 15 with its block support 17 and the hat block 16 is in downward position; as this brim-stretching operation is carried on, steam may be admitted, under controls hereinafter described, through the conduit 32 (Figure 5) to the passage 34 in the hub 18 and through the apertures 33 into the interior of the block support, whence it moistens and heats the hat body to which it is emitted through the perforations in the wall 24 and hat block 26, to soften and make more easily workable and to avoid tearing the fur felt of the hat body. These initial steps thus also insure initial working of the brim into scoped contour, a contour preferably maintained by other coactions throughout the rest of the steps.

The actuation of the collar 63 thus to pull out the brim is preferably achieved manually for it is desirable that the operator have opportunity to exercise discretion as to the rate and extent of pulling out, the extent of pulling out being otherwise also variable according to such factors as the particular size of hat body operated upon, the character of the fur felt, and the like. Accordingly, it is preferred to provide a suitable manually operable actuating means, conveniently in the form of a hand wheel 95 (Figures 2 and 4) positioned for convenience and ease of access, as at the front of the left side, as viewed in Figure 2, of the frame or base 10.

Hand wheel 95 is mounted upon a shaft 96 journaled in an elongated horizontal bearing 97 (see Figure 1) provided in or secured to the upper part of the left side of the frame 10 and at the inner end of the shaft 96 is a worm 98 that meshes with a worm wheel sector 99 (Figures 1, 5 and 4) that is keyed to the externally exposed end of a shaft 101 that extends crosswise of the frame 10 whose sides are provided with bearings to rotatably support the shaft. For speedier action, worm 98 and worm sector 99 are of large pitch like a double thread, and to prevent reversibility of drive under the tension of the hat-body, I provide a friction brake band 102 to apply a constant resistance to rotation of shaft 96, the brake band extending about a suitable cylindrical-surfaced part, as is better shown in Figure 5, and having suitable connection with a fixed part such as the bracket 109 (Figures 1, 3 and 4) so that it does not partake of rotation.

Near its middle, the shaft 101 has fixed to it arms 105 and 106 to the free ends of which are pivotally connected links 107 and 108, respectively, that extend to either side of the bearing member 14 and through suitable apertures 13^a and 13^b (Figure 2) in the frame part 13 thereof to either side of the collar 63 to which the upper ends of the links 107 and 108 are pivotally secured by suitable studs.

The shaft 96 and the bearing 97 (Figure 5) are provided with suitable coacting thrust bearing means and like parts to hold the shaft 96 against axial displacement under the reaction from the working thrust of the worm 98, and including a collar 112 on shaft 96 for coaction with the right-

hand end of the bearing 97 and a collar 110, the latter being preferably integral with the shaft 96 for coaction with the left-hand end of the bearing 97. Between the collar 110 and the hub of the hand wheel 95 there is mounted upon shaft 96 a collar 111 having an external cylindrical surface mating with the external cylindrical surface at the end of the bearing 97, either or both of these parts being counterbored to accommodate the collar 110. The cylindrical surface of the collar 111 bears graduations which, when the collar 111 is locked to the shaft 96 as by a set screw 113, may be used to give a visual indication, with reference to a fixed mark 114 of reference borne by the cylindrical surface of the bearing 97, of the extent to which the collar 110 is actuated by operation of the hand wheel 95.

For any desired vertical position of the collar 63 (Figure 2) within such range of movement thereof as maintains contact between the arms 61 of the gripping devices and the upper plane face 62^a of the groove 62, the graduation-bearing collar 111 may be set on the shaft 96 so that its zero mark coincides with the reference mark 114 on the bearing 97, and within that range, it will thus be seen, the diameter of the circular arrangement of the brim-supporting fingers 56 may be varied according to the diameter of the brims of the run of hat bodies to be operated upon. Thus the operator may make sure that the gripping devices 55 are always manually restored to the proper initial starting radius and by then operating the hand wheel 95 to raise the collar 63, thus to pull out the brim B, he can, by these graduations, give the brim of each hat body the same pulling-out processing.

During this pulling-out operation, the brim is stretched also from its initially circular shape to an oval peripheral shape, for, to swing the gripping devices 55 outwardly away from the axis of the hat body to pull out the brim to the desired extent as determined by the indicating device above described, the lower face 62^b of the collar groove 62 is brought into engagement with the arms 61 of the devices and the curvature of the face 62^b and hence the width or vertical dimension of the slot 62 are such that the front and rear gripping devices 55, being those aligned along what is to be the major axis of the oval, are swung outwardly away from the hat axis to a greater extent than those gripping devices 55 that are at the respective sides of the series, being aligned along what is to be the minor axis of the oval. In other words, with the face 62^a plane and at right angles to the axis of the collar 63, the groove 62 of the collar is of minimum width or vertical dimension at the two front and rear points of the above-mentioned major axis and from these points progressively increases in width to points respectively at the two sides, as is indicated in Figure 2. Accordingly, upward movement of collar 63 effects such relative displacement of the gripping fingers 56—64 to gradually and progressively change their circular arrangement to an oval arrangement.

Having pulled out the brim to the desired extent, tube 15 is now made to rise so as to carry the perforated hat block 26 into what is to be the crown C of the hat body H but at the same time a band ring 117 (see Figure 2) is brought downwardly externally of crown portion C and into engagement with the pulled-out brim B adjacent the band or side portion of the crown C; these movements are initiated by the operator, as 75 is later described, and take place in timed rela-

tion to each other, by appropriate controls and actuating mechanisms.

Considering first how the tube 15 is raised to raise the perforated hat block, there is provided a cross rod 118 (see Figure 2) extending between and supported by the two sides of the frame 19 and forming a fulcrum or pivotal support for a lever 120 (see also Figures 2 and 4) which may be bifurcated as shown in Figure 2 and having supported in its ends rollers 121 which engage the underface of the lower end cap 37 of the tube 15. The forked or bifurcated form of lever 120 will thus be seen to permit the accommodation therebetween of the downwardly projecting end of valve stem 36 and part of the valve lifter lever 38 that coacts with the stem 36.

The other arm 122 of lever 120 carries at its end a roller 123 that is in engagement with a cam 124 mounted and actuated as later described to actuate the lever 120 in turn to actuate the tube member 15.

The band ring 117 (Figure 2) is a strong metal oval-shaped annulus or element which is manually placed in position upon the pulled-out brim B and its internal shape is an oval of substantially the desired shape and size which the junction between the brim B and crown C is ultimately to have. It is preferably also scoped to conform with the scope of the other parts above described. It is acted upon by a band ring depresser, indicated in Figure 2 at 126, which comprises a strong metal hood-like member, open at the top as at 127, and internally dimensioned to be materially larger than the dimensions of the hat block 26 so as to leave adequate space between it and the exterior face of the crown portion C of the hat, and its lower end edge or face is oval and engages against the upper face of the band ring 117. Where the upper face of ring 117 is curved or scoped, the lower edge of depresser 126 preferably conforms to the curvature or scope of ring 117.

The depresser member 126 is carried by a cross frame 130 having at its ends vertically elongated guiding bearings 131 and 132 in slidable engagement with the vertical guide bars 73 and 74 respectively. Bearing elements 131-132 are provided with trunnions 133 and 134, respectively, to which are pivotally connected the upper ends of connecting rods 135-136 respectively. The latter extend downwardly and externally along the respective sides of the base 10 and at their lower ends are pivotally connected in any suitable way to levers 137 and 138 on the outside of the frame sides and extending rearwardly thereof where they are fixed or keyed to the externally exposed ends of a rocker shaft 140 which is rotatably supported in suitable bearings provided or formed in the sides of the base 10 (see Figure 1).

Up and down movement of the connecting rods 135-136 and hence of the depresser 126, the latter being nicely guided by the vertical guide posts 73-74 and by them always maintained coaxial with the axis of the hat block 26 and its carrier and tube member 15, may thus be effected by appropriately controlling and actuating the shaft 140, preferably by oscillating or rocking it about its axis for which reason I term it a "rocker" shaft. Such drive of the shaft is preferably effected by a cam 141 (see Figure 3) that is secured or keyed to the outwardly extending end of a shaft 142 that is rotatably supported in suitable bearings formed or provided in the two sides of the base 10, it being shaft 142 upon which, intermediate of the sides of the base 10, the above-

described cams 43 and 124 (see Figure 4) are mounted and keyed.

Cam 141 (Figure 3) coacts with a roller 143 suitably mounted in or carried by lever 138, preferably at a point intermediate of the length of the latter, cam 141 being suitably shaped to effect repetition of up and down strokes of the band ring depresser 126 in coaction with the cam roller or follower 143.

Where the cam 141 is of the peripheral type, as in the illustrative embodiment, suitable means are provided to maintain the cam follower 143 in engagement with the cam periphery and this may comprise a relatively long heavy spring 144 having one end secured to a lug-like lever arm extension 145 of the lever 138 and having its other end anchored to the base 10. Preferably, provision is made for adjusting the tension of the spring and that may be embodied in the spring anchorage. Thus the other end of the spring may be secured to the forked end 146 of the threaded rod 148 that passes freely through a hole in a lug 149 in the base 10, the threaded rod 148 having suitable nuts 150, preferably to either side of the lug 149, whereby the rod 148 may be shifted axially and locked in adjusted position, correspondingly to fix the tension of the spring 144.

The spring 144 is of sufficient power to swing the shaft 140 and its lever arms 137-138 in clockwise direction as viewed in Figures 3 and 4 and to lift and urge the connecting rods and depresser 126 upwardly, all as limited or determined or opposed by the peripheral cam 141 whose shape is substantially or generally like that shown in Figure 3.

Thus cam 141 has a portion 141^a of minimum radius corresponding to which depresser 126 assumes an uppermost position, that portion merges into a portion 141^c of materially greater radius whence follows a portion 141^d of gradually increasing radius but within that arc the portion 141^d is broken up into a number of successive high and low points corresponding to which, as the cam rotates, the depresser 126 is given several relatively rapid cycles of relatively rapid strokes of up and down movement, whence the portion 141^d merges into a portion 141^b of maximum radius at which depresser 126 is in lowermost position, this radius then merging into the portion 141^a of minimum radius.

Cams 141, 43 and 124 are fixed to cam shaft 142 in fixed angular relationships to one another as are also several other cams. Thus there is a cam 152 on cam shaft 142 that coacts with a lever 153 pivotally supported by the base 10 as by a stud 154 and arranged to actuate a valve 155 interposed between a suitable source of steam supply indicated at 156 and the above-described flexible conduit 32 that leads to the chamber 31 in the base of the block supports 17 as above described. Valve 155 is preferably a biased valve of any suitable construction so as to be self-closing; thus it may be a spring-loaded valve and its stem 157 is connected in any suitable way to one end of the lever 153. Actuation of lever 153 in a direction to overcome the spring-bias of the valve thus opens the valve while reverse actuation of the lever allows the spring of the valve to close it, the spring acting also to bias the lever 153 itself if desired.

Lever 153 is provided with a cam follower 158 of any suitable construction to coact with the cam 152 whereby the rotation of the cam can open and hold open the valve or permit the spring

of the valve to close it and hold it closed, according to the conformation of the cam. Preferably the lever 153 is also arranged to be manually actuated as by a foot treadle 160 suitably pivoted upon a lower portion of the frame 10 and connected to one end of the lever 153 as by link 161. These relationships are such that the valve may be manually opened and held open throughout such portion or portions of the cam 152 corresponding to which the valve 155 is closed and which allow of manual movement of the lever in valve-opening direction, the cam 152 being therefore preferably of the peripheral type.

Another cam carried by cam shaft 142 is cam 163 which is illustratively of the peripheral type and is of constant radius throughout excepting for two angularly-spaced projecting parts 163^a and 163^b. This cam is to take part in the control of the drive of the apparatus which is preferably driven by an electric motor 164, a description of the driving and circuit and control connections of which at this point will aid in understanding the action of cam 163.

Motor 164 is preferably of the type that embodies an electrically-controlled brake and that has built into it a suitable reduction gearing, the terminal shaft 165 of which carries a gear 166 which meshes with a larger gear 167 keyed to the cam shaft 142 at a suitable point intermediate of the ends of the shaft and preferably adjacent one of the sides of the frame 10 between which sides the motor is mounted and secured by any suitable means not shown so as to be substantially housed within the box-like base 10 itself. The brake for the motor and its control are not shown in detail and are simply diagrammatically indicated at 168 and it may be of any suitable electro-magnetically controlled type such as one in which de-energization of the brake control winding permits a spring or the like to put the brake on while energization of the winding overcomes the bias of the spring and releases the brake, such an arrangement having the advantage that the control winding need simply be connected, as by conductors 169—170 to the motor circuit 171—172—173 on the motor side of the main motor switch generally indicated by the reference character 174 and conveniently housed in a casing 105 mounted within the base 10 adjacent the motor.

Motor switch 174 is electro-magnetically actuated by a solenoid winding 175 and is of any suitable mechanical and electro-magnetic construction or arrangement of the type in which successive substantially momentary energizations of the solenoid winding alternately open and close the switch.

A suitable form of such switch is diagrammatically indicated in the drawings and it may comprise a suitably guided member 177 which insulatingly carries a suitable number of contact elements with which to bridge or unbridge corresponding pairs of fixed contacts. The solenoid winding 175 is provided with a core 178 that is connected by a link 179 to a tumbler element 180 that is rotatably supported on a fixed pivot or pin 181, the line of the pivot 181 and of the pivot point 182 of link 179 being along the bisector of the angle made by the side edges 180^a and 180^b of the element 180 and the pivot 181 being in line with the axis of core 178.

Tumbler element 180 has projecting from it a stud or pin 183 that engages in a transverse slot 184 of the vertically-guided contact-carrying member 177.

In the position shown, the contact-carrying member 177 is in lowermost position and the switch is open, and the parts are so proportioned that in this relationship solenoid core 178 rests with its lower end upon the side edge 180^a of the tumbler element 180.

If winding 175 is now energized momentarily, core 178 is quickly pulled up and starts, through link 179, to rotate the tumbler element 180 in counterclockwise direction, pin 183 thus moving the contact member 177 upwardly. The momentum of the upward movement of core 178 is sufficient in turn to give the tumbler element 180 sufficient momentum to carry the link pivot 182 to the left of the line of the axis of core 178 and hence to the left of the fixed pivot 181, the downward movement of core 178 that takes place upon de-energization of winding 175 thereby completing the counterclockwise rotary movement of part 180 which by now presents the side edge 180^b in the path of downward movement of core 178 which comes to rest thereon; at the same time, pin 183 continues its lift of the contact-carrying member 177, bringing it into uppermost position where the switch contacts are bridged, pin 183 coming to rest at a point 180° displaced from the position shown in the drawing.

The switch thus remains closed, a subsequent momentary energization of winding 175 causing the just-described sequence to be reversed, thus opening the switch and thus returning the parts to the positions shown in the drawing.

In the drawing, the power side or terminals of the main motor switch 174 are indicated at 191—192 and 193 and they lead to any suitable source of electrical energy, the circuit being illustratively a 3-wire circuit; from the power side of the switch 174, the switch winding 175 may be energized under the control of suitable switches, one of which is indicated at 194 and is constructed and arranged in any suitable way to be actuated by the above-described cam 163 on the cam shaft 142.

As is diagrammatically indicated in the drawing, the switch 194 may comprise two fixed contacts and a bridging contact 195, the latter actuated by a bell crank lever 196 suitably mounted in coacting relation to the cam 163, suitable means such as a spring (not shown) being employed to bias the lever 196 and hence its cam follower portion always against the cam periphery of cam 163, the bias being in a direction to open the switch 195.

Another switch for controlling the energization of switch winding 175 comprises a push button switch 197 suitably mounted on the base 10 within easy reach of the operator.

The contact-carrying member 177 of the switch 174 is provided with a contact-bridging member 198 that coacts with two vertically spaced pairs of contacts so that one pair is bridged while the other pair is not bridged according to whether the contact-carrying member 177 is in uppermost or lowermost position; cam control switch 194 is in circuit with one of these pairs of contacts and the manual switch 197 is in circuit with the other pair of contacts.

More specifically, when the main switch 174 is open and hence member 177 is in lowermost position, bridging member 198 bridges the lower pair of contacts and control of the switch winding 175 is thereby placed in the push button switch 197 which is thus a "start" switch. The corresponding circuit extends from main line conductor 192, conductor 200, winding 175, lower

contacts and bridging member 198, conductor 201, push button switch 197 and then by way of conductor 202 to main line wire 193.

If the normally open push button switch 197 is now actuated, switch winding 175 is energized to close the main switch and to start the motor 164 and hence to start the drive of the driving and cam shaft 142, the brake control winding being thereby energized to release the brake and to hold it released as long as the circuit of the motor remains closed by the motor switch 174.

The actuation of switch 174 in closing position, thus to move the contact-carrying member 177 into its uppermost position, shifts the bridging member 198 out of engagement with the lower pair of contacts, thus removing the circuit from the control of start switch 197, and moves bridging member 198 into bridging relation to the upper pair of contacts and thereby places the circuit of winding 175 under the control of the cam control switch 194. This latter circuit extends from power line 192, conductor 200, winding 175, bridging member 198 and the upper pair of contacts, conductor 203, switch 194, conductor 204 and thence back to the other power line 193. Cam control switch 194, when actuated into closing position subsequently, may thus energize main switch winding 175 to cause the main switch and motor circuit to be opened, the accompanying de-energization of the brake control winding allowing the brake to be promptly applied and the motor shaft quickly brought to a stop, thus avoiding over-drive of the cam shaft 142. Opening of the main switch 174 removes the control of winding 175 from the cam switch 194 and restores the control to the start switch 197.

Considering now a typical cycle of operation, the starting or "at rest" positions of the various parts are as follows: the main motor switch is open, contact-carrying member 177 being in lowermost position and bridging member 198 therefore bridges the lower pair of contacts and places the control of the main switch in the start switch 197. Band ring depresser 126 is in its uppermost position, cam 141 being in a position where its portion 141a (of minimum radius) is presented to the cam follower 143, levers 137-138 being hence in their positions of extreme uppermost swing under the bias of spring 144 and depresser 126 being thereby held in uppermost position.

The vertically-sliding tube 15 carrying the block support 17 with the desired block 26 assembled to it as above described, is in lowermost position, being engaged by a portion of cam 124 that is of minimum radius; biased latch 49 is, of course, out of engagement with the lower end cap 37 of the tube 15, but is in biased position and ready to be cammed into catching and holding relation to the end cap 37 when the tube 15 is later on raised by cam 124 and lever 120-122. This downward position of tube 15 and of end cap 37, the latter carrying the valve control lever 38, likewise insures that the cam follower 42 of the lever 38 is out of range of actuation by the cam 48; valve 35, therefore, is closed. Cam 152, by which the spring biased and normally closed steam valve 155 may be actuated is in a position to present to the cam follower 158 on lever 153 a portion of its cam periphery that is of small radius so that the valve control lever 153 may be operated by the foot treadle 160. Switch cam 163 is in a position where one of its projecting parts, namely, part 163a has just been moved out of engagement with the cam follower of switch lever 196, the braking

effect of the brake 168 on the motor 164 being so adjusted that the motor, upon opening of its circuit, and hence the cam shaft 142 and cam 163 can coast sufficiently to ride out of engagement with the switch lever whichever part 163a or 163b of the cam has been instrumental in closing the switch 194; for similar reasons, the peripheral extent of these cam portions is relatively small.

With block support and tube 15 in lower position, suction port 47 in tube 15 is closed, gripping devices 55 are open in that the gripping fingers 64 thereof are in upstanding position, hand lever 91, which controls them being in a position to hold the finger-controlling ring 72 in uppermost position.

Collar 63 is in lowermost position and hence arms 61 of the finger-carrying levers 57-61 are in engagement with the upper face 62a of the groove 62, thereby fixing the companion gripping fingers 56-64 of the entire series of gripping devices 55 in a circle. The effective diameter of this circle, determined by the links 67 with which the peripheral edge of the circular hat brim B engages when the hat H is inserted, is made to suit the diameter of the brim by the calibrated or indexed setting of the hand wheel 95 as above described.

The hat body is now inserted, with the circular hat brim resting upon the upper faces of the fingers 56 and being "centered," as it were, by the links 67 which define a circle just about equal to the diameter of the brim, thus making sure also that each gripping device 55 grips the same radial extent of the outer portion of the brim. The operator now actuates hand lever 91, thus to move the ring 72 that controls the upper gripping fingers 64, downwardly, thus to swing these fingers 64 against the upper face of the peripheral portion of the brim B and also to tension the springs 70 to maintain a gripping tension on the movable fingers 64 and thus securely hold the brim about its periphery.

The operator now turns the hand wheel 95 to move the collar 63 upwardly and hence move the gripping devices 55 outwardly, and during this operation be steps upon the foot treadle 160 to open the steam valve 155 at such intervals or for such duration of time as is dictated by his judgment, bearing in mind such factors as the quality and character of the felt of the hat body, its weight, the extent of pulling out of the brim, etc. As the hand wheel 95 is thus rotated, to an extent determined by the graduations or indexing above described, the geometric arrangement of the gripping devices 55 undergoes a transition from the initial above-mentioned circular arrangement to the above-described oval arrangement, it being noted that these operations, including the initial gripping of the brim B of the hat, are accompanied by the "scoping" of the hat brim inasmuch as, in the preferred arrangement and as above described, the upper faces of the lower gripping fingers 56 are at progressively different heights to correspond to an approximation of the curvature, called the "scope," desired to give the brim.

The hat body during these operations, is, due to the steam treatment which it gets by the steam emitted through the perforations in the part 24 of the block support and in the block itself, raised in temperature and moistened, thus conditioning its inter-felted and inter-locked fur fibres and the fur felt fabric itself for quicker and readier accommodation, without tearing or damage, to the

distortions and tensioning to which the hat body is subjected by the apparatus. Having pulled out the brim to the desired oval extent, as indicated by the graduations by which the amount of turning of the hand wheel 95 may be gauged, the operator now places the band ring 117 onto the brim and then presses the push button "start" switch 197, whence the cam shaft 142 commences to turn, slowly rotating in unison the various cams mounted thereon. Cam 141, with portion 141^a in engagement with cam roller 143 at the start, rides portion 141^c into engagement with the cam roller 143, thus bringing the depresser 126 down into engagement with the band ring 117 and concurrently therewith cam 124 rides its portion of gradually increasing radius into engagement with the cam follower 123 on lever 120—122, thus raising the tube 15 with the hat block 26, the upward movement of the block 26 entering the block into the crown portion of the hat body under the coaction of the band ring 117 which is engaged and held, and according to circumstances moved downwardly somewhat, by the descending depresser 126. Tube 15 is raised by cam 124 sufficiently for latch 49 to catch and hold the tube 15 and hat block support in uppermost position, and at the same time, the upward movement of tube 15 carries valve stem lever 38 upwardly to bring its cam follower 42 within the range of actuation by cam 43. Steam valve control cam 152, during the just-described operations, raises and holds the lever 153 in position to open and hold open the steam valve 155, so that the hat body is kept moist and hot as the block is entered into the hat body, the crown portion of which is thus pulled, tensioned and in effect conformed to the hat block, it being noted that the band ring 117 is also scoped to conform to the scope of the gripping devices 55. During the latter portions of the above-described operations, the undulated portion 141^d of the cam 141 rides into engagement with the cam roller 143, that portion being of generally the same radius as the portion 141^c at the start and gradually increasing in radius as rotation continues through portion 141^d. Due to the high and low points in the latter, the depresser 126 undergoes several relatively rapid cycles of rapid up and down strokes in order in effect to "felt" or work the heated and moist crown portions of the hat body over the hat block and the brim portion into substantially 90° relation to the side parts of the crown C; during these latter reciprocating movements of the band ring and its depresser, tube 15 and the hat block complete their upward movement under the control of cam 124 which has a portion of maximum radius and of short peripheral extent to hold these parts uppermost and to give the latch 49 time to engage the bottom end cap 37 of the tube 15 and thus lock these parts in uppermost position. Depending upon relative positions of the cams or upon the specific shape of cam 124, the hat block reaches its uppermost position before or after the commencement of the reciprocations of the depresser 126 and the band ring 127, as may be desired.

With the tube 15 and hat block now locked in uppermost position by latch 49, steam valve control cam 152 closes the steam valve 155, but this action preferably does not take place until just after portion 141^b of cam 141, being a portion of maximum radius, has effected by way of depresser 126 completion of the downward movement of the scoped band ring 117 into substantially the scoped plane of the outer portions of the brim B

that are held by the gripping devices 55, thus to conclude the stretching, tensioning, or blocking of the crown C over and onto the hat block 26 and the tensioning and pressing of the brim B against the scoped brim support 24. Thus also the desired angular relation between the brim B and the sides of the crown C is completed.

The upward movement of tube 15 and its locking by the latch 49 brings and holds the port 47 in registry with the port 46 which is connected by the pipe 45 to the source of low pressure or suction. As this registry of the ports is effected, valve 35 remains closed, but is thereafter opened by the cam 43 which engages the roller 42 on the valve lever 38 to tilt the latter clockwise and thus lift the valve stem 36 and valve 35. Any steam or water vapor that remains in the tube 15 and in the space within the block support and underneath the hat body is withdrawn through the pipe 45 and cool and dry air from the atmosphere is drawn down through the crown C and brim B of the hat body, through the perforations in the block 26 and in the wall 24, thus cooling off and to some extent drying the fur felt of the hat body and in effect fixing the fabric and its interlocked and interfelted fur fibres in the positions and shapes to which the crown has been conformed by the block 26 and the brim B has been conformed by the scoped perforated wall 24, all in coaction with the scoped band ring 117 and the scoped and oval arrangement of the outwardly tensioned and held gripping devices 55.

Just about the time that valve 35 is opened, which happens at the point of maximum depression of the depresser 126 by portion 141^b of the cam 141, projecting portion 163^a of cam 163 engages the stop switch lever 196 to close the switch 194, thereby to open the main line switch 174 and effect stopping of the motor and the apparatus as above described, part 163^a of the cam riding out of engagement with the cam lever 196 before final stoppage results. The hat body remains in the relationship last above described, all of the moving parts being at rest, but with valve 35 open and hence with continued drawing by the low pressure or suction apparatus of cool and dry air through the tautly conformed crown and brim. The operator allows the apparatus to remain in this condition for an appropriate length of time which may vary according to the character, quality, thickness, size and other factors of the fur felt hat body and hence the operator exercises appropriate judgment to suit the circumstances, whence he actuates the push button start switch 197, again starting the motor and starting the apparatus.

This second starting of the apparatus moves cam 43 out of engagement with the valve lift lever 38, thus closing valve 35 and cutting off the suction apparatus. Cam 141 rides its point of maximum radius in the portion 141^b along the cam roller 143 to bring the portion 141^a of minimum radius gradually into coaction with the cam roller 143 in order thus to raise the depresser 126 but before the depresser 126 starts moving upwardly, the gripping devices 55 are made to release the brim. This release of the gripping fingers is effected by a cam 206 keyed to main cam shaft 142 and arranged to actuate the shaft 90 to swing eccentrics 87 and 88 in a direction to effect upward swing of the lever arms 81—82 and hence upward movement of the finger-controlling ring 72. On shaft 90 I key a lever arm 207 provided with a roller 208 in its outer end, and on shaft 118 is pivoted a lever 209 in any

suitable way so that it may freely swing about the shaft as an axis and be held against axial movement along the shaft, thereby to present one arm 209^a thereof for engagement with the roller 208 of lever 207 on shaft 90 and to present its other arm 209^b in the path of rotary movement of the cam 206 on shaft 142.

This arrangement permits manual swinging by the lever 91 of the shaft 90 in counterclockwise direction as viewed in Figure 4, the arm 209^a of lever 209 maintaining contact with the roller 208 during the manual swing of shaft 90 and its lever arm 207. When the shaft 90, however, is swung by the hand lever 91 to move and hold the finger grip control ring 72 down, the arm 209^b of lever 209 is positioned in the path of rotary movement of cam 206 on cam shaft 142, cam 206, being somewhat like a trip or an arm, being halted just in advance of possible engagement with arm 209^b when the apparatus is first halted by the projecting part 163^a of the cam 163 controlling the stop switch 194.

Accordingly, when the operator actuates the start button 197, the suction is cut off as above described and the first portion of rotary movement of cam shaft 142 also brings trip cam 206 quickly into engagement with arm 209^b of lever 209, tilting the latter about the shaft 118 and through the other arm 209^a depressing the arm 207 on shaft 90 to a sufficient extent to rotate the shaft 90 and its eccentrics to raise the finger grip control ring 72 and thereby raise the companion or upper gripping fingers 64 about their pivots 65, thus releasing the brim. Trip cam 206, in continuing its rotary movement, rides over the end of lever arm 209^b and out of engagement therewith, the bias of lever 209, by the greater weight of arm 209^a, maintaining the latter always in engagement with the roller 208 on the lever arm 207 of shaft 90.

The brim is thus released from the grip of the gripping devices and by the time that release is completed, the depresser 126 commences upward movement to its uppermost position corresponding to the engagement of cam roller 143 with the cam portion 141^a of cam 141. Just about when the depresser reaches its uppermost position, the projecting part 163^b of stop switch cam 163 actuates stop switch 194 in turn to effect opening of the motor switch 174, halting the motor and the apparatus promptly under the braking action of the brake 168, control of the main switch 174 being by the bridging member 198 of the main switch now transferred again to the push button start switch 197.

The hat body with the block 26 and also the band ring 117 are now removed, after which the operator lowers block support 17 by lifting operating handle 52, which withdraws latch 49 from part 37, thus dropping tube 15 which carries block support 17, and also turns hand wheel 95 to restore the gripping devices 55 to their innermost positions and to their circular arrangement, to an extent as is indicated by the graduations or indexing related to the hand wheel 95 as above described, thus conditioning the gripping devices 55, with their upper gripping fingers 64 upstanding or in open position due to the automatic actuation thereof as just above described, for the reception of the next hat body, whence the cycle of operations above described is repeated. The ensuing actuation of hand lever 91 to raise the collar 63 at an appropriate point in the sequence of steps restores the lever 209

to a position such that its arm 209^b is again in the path of rotary movement of the trip cam 206 during the ensuing cycle of operations.

Effective and efficient "blocking" may be achieved with nicety and uniformity of action of the various parts of the apparatus. The mounting and actuation of the various parts, such as the depresser and the gripping finger control ring are nicely balanced individually as well as in relation to each other, the upstanding parallel guide bars 13-14 insuring rigidity of mounting and dependability of guiding of these parts to insure repeated uniformity of action and operation, while the driving linkages and related actuating parts therefor aid in achieving these advantages during actuation of the various parts.

Furthermore, the apparatus will be seen to be desirably automatic in certain of its actions and advantageously automatic in halting certain of its actions at such points where it is desirable to bring the judgment and skill of the operator to bear upon the processing of the hat body and subsequent removal and replacement thereof, these features being so correlated as to leave the operator those selected steps as to which his skill and judgment can best contribute toward quality of result, the steps performed automatically by the apparatus contributing toward efficiency of the result.

It will thus be seen that there has been provided in this invention an apparatus in which the several objects hereinbefore set forth together with many thoroughly practical advantages are successfully achieved.

It will be seen that the apparatus is of dependable, reliable, and accurate action in "blocking" the hat body to the desired dimensions and conformation and is operable with nicety and safety of action upon the particular quality, texture, weight, thickness or the like of the fur felt of the hat body. While the apparatus is in many respects fully automatic throughout several portions of a complete cycle, its controls are such that the operator may, according to his judgment as dictated by such factors as just mentioned, interject such variables in the processing and at variable lengths of time intervals as are suited to the particular circumstances. And thus it will be seen that high efficiency and greater dependability and uniformity of quality of result may be successfully achieved.

As many possible embodiments may be made of the mechanical features of the above invention and as the art herein described might be varied in various parts, all without departing from the scope of the invention, it is to be understood that all matter hereinabove set forth, or shown in the accompanying drawings, is to be interpreted as illustrative and not in a limiting sense.

I claim:

1. A hat blocking apparatus comprising a perforated form having a crown portion, a band ring, releasable brim-gripping devices grouped about the axis of said form for gripping peripheral portions of the brim of a hat body, means for actuating said devices radially outwardly from said axis to stretch the brim, a movable support for said perforated form, said support having a path of movement along said axis in a direction toward said band-ring, means providing a source of fluid for conditioning the hat body, and means for controlling the flow of fluid from said source to the hat body comprising two relatively slidable members each having a port therein whereby the

port in the one may be brought into or out of registry with the port in the other according to the relative slideable movement between said two members, and means responsive to movement of said support for effecting relative sliding movement between said two members.

2. A hat blocking apparatus comprising a form having a crown portion, a band ring, releasable brim-gripping devices grouped about the axis of said form for gripping peripheral portions of the brim of a hat body, means for actuating said devices radially outwardly from said axis to stretch the brim, a motor driven mechanism having a manual start switch control and a self-actuated stop switch control with means causing actuation of the stop control switch at the completion of a cycle of operation and also at a point intermediate of the start and end of said cycle, whereby said manual control has to be actuated first to start the cycle and later to complete it after said stop control is actuated at said intermediate point, said mechanism comprising means operating during the first portion of said cycle to heat and moisten the hat body, to effect relative movement axially between said form and said ring in a direction to conform the hat body to said form, then to halt heating and moistening of the hat body, and then to cool said hat body, and said mechanism comprising means operating during the second portion of said cycle to halt the cooling of the hat body and to effect retrograde relative movement between said band ring and said form.

3. A hat blocking apparatus comprising a hat form, a band ring, a plurality of brim-gripping devices having means movably supporting them in a group about the axis of said hat form, each of said devices having an arm projecting therefrom, portions of all of the arms being equi-dimensional, and means comprising movable means having a cam groove of varying width in which said equi-dimensional portions of said arms engage for displacing said gripping devices radially to different extents upon movement of said movable means in one direction to thereby arrange said gripping devices in substantially an oval and operating upon movement of said movable means in an opposite direction to displace said gripping devices and position them to conform substantially to a circle.

4. A hat blocking apparatus comprising a hat form, a band ring, a plurality of brim-gripping devices having means movably supporting them in a group about the axis of said hat form, each of said devices being in the form of a bell crank lever pivotally mounted with the free arms thereof projecting transversely of said axis, all of said free arms having equi-dimensional terminal portions, and a member having means mounting it for movement along said axis and presenting two spaced means between which said equi-dimensional portions of said arms extend for thereby effecting radial displacement of said devices inwardly or outwardly, one of said spaced means having a conformation to displace said devices radially in differing amounts to give the group of the devices the conformation of an oval and the other of said spaced means having a conformation to displace said arms and said devices to cause the latter to be grouped in a circle.

5. A hat blocking apparatus comprising a box-like frame having upstanding therefrom two laterally spaced guide bars, a block support, means mounting and guiding said block support for movement up or down along an axis intermediate

of said guide bars, releasable brim-gripping devices having means movably mounting them in a group about said axis for gripping peripheral portions of the brim of a hat body, movable ring-like means having slideable bearing guides on said bars and having connections with said devices for controlling the gripping action thereof, a band ring having means provided with sliding bearings on said upstanding guide bars for depressing it downwardly along said axis, and driving mechanism carried by said frame and having operating connections adjacent each guide bar with said ring-like means and with said band ring depressing means for effecting actuation thereof, said mechanism comprising means for effecting upward movement of said block support in timed relation to the actuation of said depressing means.

6. A hat blocking apparatus comprising a hat form having a scoped crown portion, a scoped band ring, a plurality of identically dimensioned releasable brim-gripping devices having means mounting them at different elevations to form a scoped group about the axis of said form, said devices being movable individually toward or away from said axis without change in relative elevations thereof as provided by said mounting means, means for moving said devices radially outwardly to stretch the brim, and means to effect relative movement axially between said form and said band ring in a direction to conform the hat body to said form.

7. A hat-blocking apparatus comprising a perforated form over which to receive a hat body, releasable gripping devices for gripping edge portions of the hat body, means for effecting relative movement between said form and said gripping devices to stretch the hat body over the form and including a slideable tube having a port in a portion of the side wall thereof and having means for slidably guiding it for movement whereby said side port partakes of displacement according to the slideable movement of said tube, and means including said tube and said side port and comprising a member having a port relative to which said side port of said slideable tube is movable to bring said ports into or out of coacting relation, for supplying to the hat body a fluid for conditioning it.

8. A hat-blocking apparatus comprising a perforated form over which to receive a hat body, releasable gripping devices for gripping edge portions of the hat body, means for effecting relative movement between said form and said gripping devices to stretch the hat body over the form and including a slideable tube having a port in a wall thereof and having means for slidably guiding it for movement, said tube communicating with the interior of said perforated form and having means supporting the form for movement therewith, said guiding means having port means with which the tube port means is brought into or out of registry according to the sliding position of the tube, and means connecting said port means of said guide means to a source of fluid.

9. A hat-blocking apparatus as claimed in claim 5 in which the connections between said ring-like means and said brim-gripping devices comprises a plurality of springs, one for each device.

10. A hat-blocking apparatus comprising a hat form, a band-ring, a plurality of brim-gripping devices, means movably mounting said devices in substantially a group about the axis of said form, each device having a movable gripping finger,

and mechanism comprising a spring element for each device through which the gripping actuation of said gripping finger is controlled, and a common means for acting upon all of said spring elements to thereby actuate all of said gripping fingers.

11. A hat-blocking apparatus comprising a hat form, a band-ring, releasable brim-gripping devices having means movably mounting them in a group about the axis of said hat form for gripping peripheral portions of the hat body, each of said devices including at least one movable gripping finger, ring-like means having means movably mounting it for movement substantially along the axis of said hat form and having a plurality of leaf springs, one for each device, connections between each leaf spring and a movable gripping finger of a device, and means for effecting relative axial movement between said hat form and said band ring.

12. A hat-blocking apparatus comprising a hat form, a band-ring, a plurality of substantially upstanding lever-like members each provided at its upper end with releasable brim-gripping means, means pivotally supporting said lever-like members in a group about the axis of said hat form for gripping peripheral portions of the hat body, each of said brim-gripping means including at least one movable gripping finger, ring-like means having means mounting it for movement substantially along the axis of said hat form and having projecting therefrom a plurality of cantilever spring elements, one for each of said lever-like members, a plurality of links, one for each lever-like member and each extending lengthwise along its lever-like member said links being connected at their upper and lower ends, respectively, to said gripping means and to said cantilever springs, and means for effecting relative axial movement between said hat form and said band-ring.

13. A hat-blocking apparatus as claimed in claim 12 in which said lever-like members are pivotally mounted adjacent their lower ends on said first-mentioned mounting means and are provided with means for moving them in unison about their pivots thereby to position them in their grouping nearer to or farther away from said axis, the connections between said links and said cantilever springs being located closely adjacent the respective pivots of said lever-like members, whereby said cantilever springs may compensate, during gripping action of said fingers, for relative shifts of the parts due to pivotal movement of said lever-like members.

14. A hat-blocking apparatus comprising a hat form, a band-ring, releasable brim-gripping devices grouped about the axis of said hat form for gripping peripheral portions of the hat body, a motor-driven mechanism having a manual start switch and a stop switch and including a driven cam having spaced cam portions to respectively actuate the stop switch at the completion of a cycle of operation and to actuate it at a point intermediate of the start and end of said cycle, whereby said manual switch has to be

actuated first to start the cycle and later to complete it after said stop switch is actuated by the first of said spaced cam portions, said mechanism comprising means operating during the first portion of said cycle to heat and moisten the hat body, to effect relative movement between said form and said ring to conform the hat body peripherally gripped by said devices to said form, then to halt heating and moistening of the hat body, and then to cool said hat body, and said mechanism comprising means operating during the second portion of said cycle to halt the cooling of the hat body and to effect relative disengaging movement between said band-ring and said hat form, braking means operable to slow down and halt the drive of said mechanism, and means responsive to actuation of said stop switch for controlling the actuation of said braking means.

15. A hat-blocking apparatus comprising a frame having upstanding therefrom two laterally spaced guide posts, a block support, means mounting and guiding said block support for movement up or down along a vertical axis intermediate of said spaced guide posts, releasable brim-engaging devices having means mounting them in a group about said axis for gripping peripheral portions of the brim of a hat body, a band-ring to take about a block supported by said block support and adapted to engage the hat body throughout a ring-shaped region intermediate of the tip of the hat body and the peripheral portions gripped by said gripping devices, a rigid cross-beam bridging the space between said spaced guide posts and having spaced bearing elements co-acting with said guide posts whereby said cross-beam is mounted for reciprocating movement, said cross-beam having means substantially coaxial with said axis for engaging said band-ring to transmit reciprocating movement thereto in up and down strokes, and mechanism for reciprocating said cross-beam and including operating connections that apply moving forces to said cross-beam in directions substantially aligned with said spaced posts.

16. A hat-blocking apparatus as claimed in claim 15 in which said operating connections comprise two links extending vertically and substantially aligned, respectively, with said guide posts and having connection at their upper ends with said cross-beam, driven cam means having an undulating cam portion, lever means having connection with the lower ends of said links, and cam follower means coacting with said undulating cam portion for oscillating said lever means.
